UNITED STATES PATENT OFFICE.

DAVID R. KNAPP, OF POTTSVILLE, PENNSYLVANIA.

SAFETY LIMIT-SWITCH.

1,299,839.

Specification of Letters Patent.

Patented Apr. 8, 1919.

Application filed December 28, 1917. Serial No. 209,277.

To all whom it may concern:

Be it known that I, DAVID R. KNAPP, a citizen of the United States, residing in Pottsville, in the county of Schuylkill and 5 State of Pennsylvania, have invented certain new and useful Improvements in Safety Limit-Switches, of which the following is a specification.

My invention relates to that class of devices used on electric operated hoists wherein 10 it is desired to automatically stop the hoist after the hook or block has reached a position that a further movement would engage the hook or block against the hoisting drum, thereby damaging the hoisting structure or 15 breaking the hoisting rope and impairing the safety of the workmen from the falling material.

On account of restricted head room or 20 travel of the hoisting hook, in some cases it is necessary for the hook to raise to a point very close to the drum and in other cases the limit of travel can be as far as several feet from the drum. In either case there is 25 danger of the power being still applied after the hook has reached this danger position, due to an inoperative controller, carelessness or many other causes, which obviously results in considerable damage and sometimes 30 loss of life if the ropes should rupture and allow the parts to fall.

In some forms of safety limit switches the circuit is opened by some means operative 35 with the hoist and the switch is reset by hand. This is objectionable due to the fact that the operator may have to climb considerable distance or that the position that the machinery is in may subject him to great danger or that the loss of time required may 40 be of vital importance.

It is therefore the object of my invention to provide; first, a switching mechanism that will provide circuits to automatically stop the motor after the hook or block has raised 45 to a predetermined height; second, to provide an electric dynamic circuit on the armature when the switching mechanism is operated to insure a quick stop in case the danger limit is set close to the drum; and third, to 50 provide a means to close the switch and lower the block from the operator's controller, and fourth, to provide a limit switch that will not open the motor circuit when operated, thereby eliminating destructive 55 arcs on the switch.

With these objects in view my invention consists in certain novel features of construction and arrangement of parts, as will hereinafter be more fully described and pointed out in the claims, reference being 60 had to the accompanying drawings forming part thereof, and in which; Figure 1 is an elevation showing the device as applied to a hoisting drum equipped with a cable and a hook. Fig. 2 is a plan view of the switch. 65 Figs. 3 and 4 are views showing in detail the contact brush. Figs. 5, 6, 7, and 8 are views showing details of the brush holding device on the extremities of the movable arm. Figs. 9, 10, 11 and 12 are views showing in detail the brush holding device fixed on the base of the switch. Fig. 13 is a plan view of the weight showing more clearly the 70 eye bolts and the cable within. Fig. 14 is a wiring diagram showing the method of wiring the switch to a standard reversing drum controller used on hoists so as to provide a dynamic stopping circuit and also a circuit for lowering after the switch has operated. 75

In a case where the controller 50 is in 80 movable relation to the motor and switch as where the device is employed with an electric traveling crane having the control cab fixed to the crane girders, it is, of course necessary to employ trolley wires connected 85 by suitable leads to the movable parts of the circuits. In the present invention, portions of the leads 52, 55, 56 and positive lead to brake coil are utilized as trolley wires therefor, making it unnecessary to add 90 any wires to the ordinary trolley wires employed in devices of this kind wherein four are required to operate the hoist without the switch.

Referring to the figures in the drawings, 95 similar numerals of reference refer to similar parts throughout the several views, and in which the numeral 1 designates a hoisting mechanism, usually a drum provided with the necessary motive power, and said 100 drum is provided with a rope 3 and at the extremity thereof is attached the hook 2 by which the material is fastened to be lifted. It is desired therefore that when the hook 2 is a predetermined distance from the drum 105 that the automatic device be operated to cut off the hoisting power.

The numeral 4 designates an insulating base upon which the switch is mounted.

5 designates a pivot supporting casting 110

for a hereinafter mentioned switch blade and said casting is secured to said base 4 by the screw 6.

The numeral 38 designates a binding post 5 for an electrical connection. 7 designates a switch blade supported by the casting 5 and is fulcrumed thereto by the pin 8. Said switch blade 7 is provided at each extremity with a contact brush 9 and 10 which 10 forms in effect a two point switch. In apparatus of this character the contact brushes require frequent renewing and it is essential that substantial and convenient means of renewal be accomplished. This construction 15 is more clearly shown in Figs. 5 and 6 in which the ends of said switch blade 7 terminates in a protruded lip 40, and the under portion adapted to form an acute angle with the main portion of the switch 20 arm. 14 designates a clamping bar and is provided with the aperture 41.

9 and 10 designate respectively contact brushes whose shape is designed to fit snugly to the end of said switch lever and 25 to the clamping bar 14. The contact brushes are provided with an aperture 43 through which the screw 15-16 is adapted to pass. It is obvious that the contact brush is held rigid to the switch arm by the clamping 30 bar 14 which is secured by the screw 16 passing through said clamping bar and through the aperture 43 of contact brush 9 and engaging by threaded relation with the switch blade 7 by the threaded aperture 35 42, clearly shown in Fig. 6.

19 and 20 designate respectively contact brush bases rigidly fixed to said base 4 by the screws 33 and 34.

Said bases 19 and 20 are provided respectively with clamping bars 18 and 17 and with contact brushes 11 and 12.

31 and 32 designate securing screws which engage the contact brush clamping bar in fixed relation similar to that heretofore described at the end of the switch blade 7. It is obvious that the construction discloses a convenient means for securing or removing the contact brushes.

21 designates a yoke pivoted to said 50 switch blade 7 by the pin 35 and 19 designates a rod in threaded engagement with said yoke 21 and passing through an aperture in the base, where it terminates in an insulator 27, thus insulating the lever parts 55 of the switch from the hoisting mechanism.

28 designates a flexible rope secured to the insulator 27 by the screw eye 43.

29 designates a weight secured to the rope 28 by any convenient means, and said 60 weight is provided with the screw eyes 30 through which the hoisting rope 3 is adapted to pass freely. It is understood that the weight 29 can be adjusted to any relative distance to the drum by adjusting the length 65 of the rope 28.

22 designates a yoke adapted to embrace the switch lever 7 at a point opposite the fulcrum to the yoke 21.

24 designates a rod secured to the yoke 22 by threaded relation and adapted to pass 70 through an aperture in the base and 25 designates a counter weight attached to said rod 24 by threaded relation and made secure thereto by the jam nut 26. The said counter weight is of insufficient weight to overbalance the weight 29 but is of sufficient weight to close the switch after the hook has raised the weight 29. The numeral 44 designates 75 terminal lugs integral with the contact brush base 19 and 20, and 37 and 39 designate contact bolts by which terminal leads are fastened.

49 designates apertures in the base 4 for securing to some substantial support above the hoisting drum 1.

50 designates, diagrammatically, a reversing controller adapted to control the hoisting and lowering motion of the hook 2. R² designates the control resistance and R¹ designates an auxiliary resistance. The numerals 51, 52, 53, 54, 55, and 56 designate leads interconnecting said controller, safety switch and the various parts.

Having thus described the various parts throughout the several views, all of which will be understood by those skilled in the art to which this invention relates, its mode of operation will be substantially as follows:

Assuming that the safety limit switch is mounted in a fixed position over the hoisting 100 drum and that the rope 28 is adjusted in length as to place the weight 29 in a position where the safety limit switch is to operate.

The weight 29 being of sufficient weight to overbalance the counter weight 25, its 105 weight will close the contacts 9 and 11 and open the contacts 10 and 12. This will form the normal raising and lowering circuits and will be as follows: for lowering, positive line, brake, field, lead 52 to controller, lead 110 56, contacts 11 and 9, through switch blade, lead 54, armature, lead 55 to controller and thence in the usual manner to negative line.

For the hoisting motion; positive line, brake, field, lead 52, to controller, lead 55, 115 through armature in a reverse direction relative to lowering, lead 54, switch blade, contacts 9 and 11, lead 56 to controller and thence in the usual manner to negative line.

Assume the controller to be placed on the 120 up position and the hook 2 rises to a dangerous position, engaging and lifting the weight 29.

Said movement will cause the counter weight to close contacts 10 and 12 and open 125 contacts 9 and 11, and circuits will be established as follows:

Assume that the control resistance R² has been cut out and the hook is hoisting full speed.

From positive line, brake, field, lead 51, contacts 12 and 10, through switch arm, lead 53, R¹, lead 56 to controller and thence to negative line. It will be seen that this 5 circuit throws the fields and brake across the line with the resistance R¹ in series and energizes the field.

An additional circuit will be established as follows: armature, lead 55, to controller 10 on the up side, lead 52, lead 51, contacts 12 and 10, through switch arm, lead 54, back to armature. It will be seen that this places the armature on a short circuit.

The armature in such a condition with an 15 energized field will set up a strong dynamic current which will cause the armature and the hoisting drum to come to a quick stop, thus preventing any damage to the hoisting mechanism, thus accomplishing the first and 20 second objects of my said invention.

The controller is now brought to the off position which will set the brakes due to the circuit being opened, the contacts 10 and 12 will still be closed and the contacts 9 and 11 25 open. The controller is then thrown to the lowering position and a circuit will be established as follows: positive line, brake, field, lead 51, contacts 12 and 10, through switch blade, lead 54, armature, lead 55 to controller, and thence to line forming a lowering 30 circuit, the current passing through the armature in the same direction as when the switch is in the normal position. There will also be an additional circuit established as 35 follows: positive line, brake, field, lead 52, to controller, lead 56, R¹, lead 53, and combining with lead 54 from the former circuit from lead 51. This circuit is inactive due to 40 the fact that the previous circuit is shorter and has no inserted resistance.

Upon lowering the hook 2 a slight distance the weight 29 again closes the switch to its normal position as heretofore described, thus accomplishing the third object 45 of my said invention. It will be noted that the opening and closing of the switch will not be accompanied with any severe arc due to the fact that the motor circuit is never opened by the switch contacts.

50 In some forms of limit switches the motor circuit is broken by the switch which is objectionable due to the fact that a severe arc occurs. In Fig. 14 it will be seen that the current traverses contacts 9 and 11 and if 55 those contacts are opened the current will take a path through the resistance R¹ which is shunted around these contacts, therefore no severe arc can take place. It will be seen that before the dynamic circuit contacts 10 and 12 close, the contacts 9 and 11 will have 60 opened which will automatically insert resistance in the hoisting circuit which will slow down the motor to a considerable extent before the dynamic circuit is closed, thus ac-

complishing the fourth object of my said 65 invention.

It will further be apparent that an effective braking action is accomplished without utilizing the friction brake and also without changing the position of the controller 70 whereby the personal equation is entirely eliminated. The force of the dynamic effort to stop the motor depends on the strength of the field winding of the motor and the amount of current permitted to flow through 75 the resistance connected across the switch. The stronger the field, the quicker the stop. Applying this to the practical operation of the hoist it becomes evident that the life of the friction brake is prolonged by employing 80 the dynamic current to stop the motor.

I do not wish to limit myself to the exact construction as shown as certain modifications can be made without departing from the spirit and intent of my said invention, 85 but what I claim as new and desire to secure by Letters Patent is:

1. In a device of the character stated, the combination of a hoisting mechanism, a hoisting circuit and a lowering circuit for 90 said mechanism, a controller for said circuits, a normally open dynamic brake circuit, an overhoisting limit switch, means including a suspended weight to automatically operate said switch to close said braking circuit, means arranged to open a portion of the operating hoist circuit upon operation of said switch, and means to maintain the operating hoist circuit closed to prevent arcing during the operation of said switch. 95

2. In a device of the character stated, the combination of a hoisting mechanism, a hoisting circuit and a lowering circuit for said mechanism, said lowering circuit having two gaps in inoperative condition, a 105 controller for said circuits, a normally open dynamic braking circuit, a limit switch, means including a suspended weight to automatically operate said switch to close said braking circuit and one gap of said lowering 110 circuit and means to prevent arcing at said switch while the lowering circuit is maintained ready to be effective upon the closure of the other gap of said lowering circuit by the operation of said controller. 115

3. In a device of the character stated, the combination of a hoisting mechanism, a hoisting circuit and a lowering circuit for 120 said mechanism, a controller for said circuits, a brake coil common to said circuits and normally energized, two sets of contacts, a limit switch normally closing one of said sets of contacts and means operated by the shifting of said switch to the other set of contacts to retard said hoisting mechanism 125 without deenergizing said brake coil.

4. In a device of the character stated, the combination of a hoisting mechanism, a

hoisting circuit for said mechanism, a brake coil in said circuit, means automatically operable to retard said hoisting mechanism at a predetermined position and to maintain 5 said hoisting circuit closed and said brake coil energized, an open lowering circuit, means controlled by said automatic means to partially complete said lowering circuit and a controller for breaking said hoisting 10 circuit and completing said lowering circuit.

5. In a device of the character stated, the combination of a hoisting mechanism, two operating circuits for said hoisting mechanism, one of said circuits being closed to 15 operate said hoisting mechanism in one direction and the other circuit being open, a brake coil common to said circuits, means operable to form a dynamic braking circuit to maintain said operating circuit closed to 20 maintain said brake coil energized and to partially close said open circuit and a controller for breaking said closed circuit and completing the partially closed circuit.

6. In a device of the character stated, the 25 combination of a hoisting mechanism, two operating circuits for said hoisting mechanism, one of said circuits being closed to operate said hoisting mechanism in one direction and the other circuit then being open, 30 a brake coil common to said circuits, a set

of contacts common to said circuits, a switch in said circuits and controlling said contacts, means to shift said switch from one contact to the other and a resistance normally in both circuits to prevent the closed operating 35 circuit being broken and to maintain said brake coil energized.

7. In a device of the character stated, the combination of a hoisting mechanism, two operating circuits for said hoisting mechanism, one of said circuits being closed to operate said hoisting mechanism in one direction and the other circuit then being open, a brake coil common to said circuits, a 40 set of contacts common to said circuits, a switch in said circuits and controlling said contacts, means to shift said switch from one contact to the other, a resistance normally in both circuits to prevent the closed operating circuit being broken and to maintain said 45 brake coil energized and a controller for breaking either circuit and to change from one circuit to the other.

In testimony whereof I have signed this specification in the presence of two subscribers.

DAVID R. KNAPP.
